WINDOW CONSTRUCTION

Joseph V. Desmarais, New Bedford, Mass.

Application May 23, 1934, Serial No. 727,198

4 Claims. (Cl. 20—55)

This invention relates to a window construction and involves certain improvements over the construction disclosed in my prior Patent No. 1,893,763, dated January 10, 1933.

One of the objects of the present invention is to provide a construction similar to that of my prior patent but in which the side rails of the lower or inner sash and the front or inner bead of the window frame are provided with cooperating inclined surfaces which serve to maintain a tight joint between the bead and frame regardless of the shrinking or swelling of the parts and which also prevent lateral movement and rattling of the sash in the frame.

A further object is to provide an arrangement similar to that of my prior patent in which a storm sash or extra sash can be inserted in the frame below the outer sash, such storm sash being removable and replaceable from the inside of the window and being so constructed that it can be arranged in an inclined position to form a ventilator for the window.

A still further object is to provide improved means for holding the front or inner beads on the window frame and which permit the beads to be easily and quickly detached therefrom to permit the lower sash and the storm sash to be removed inwardly from the window frame.

These and other objects are attained by the specific embodiment of my improved construction illustrated in the accompanying drawings and described in the following specification.

In said drawings:

Figure 1 is a fragmentary front view of a window embodying my present improvements;

Figure 2 is a longitudinal section of the same with the inner sash in its lowermost position and the storm sash also in position;

Figure 3 is a longitudinal view of the inner face of the front or inner bead which I employ;

Figure 4 is a vertical sectional view showing the window sash elevated and the storm sash tilted inwardly in position to form a ventilator, this view also showing in dotted lines the position of the inner sash when detached from the frame and drawn inwardly;

Figure 5 is a transverse section on the line X—X of Figure 1;

Figure 6 is a transverse section on the line Y—Y of Figure 1;

Figure 7 is a perspective view partly broken away showing the construction of the movable strips arranged in the window frame, one on each side of the outer window sash;

Figure 8 is a fragmentary perspective view of the upper end of the front or inner bead which I employ; and

Figure 9 is a section on the line 9—9 of Figure 3.

Referring in detail to the various features of

my construction, the window frame comprises vertical side members 10 which may be formed of plain strips or boards of uniform thickness. A sill 11 is secured between the lower ends of the side members 10 and a top member 12 is secured to the upper ends of said side members. A facing or finishing strip 13 is secured to the inner edge of the side members 10 and similar strips 14 may be secured to the rear edges of such members.

Adjacent the rear edge of each of the frame members 10 and suitably secured to the inner face thereof is a rear bead 15, these beads extending from the top to the bottom of the window frame.

The outer or upper sash of the window is arranged in front of the beads 15, and this sash includes side rails 16, an upper rail 17 and a lower rail 18. Between each of the side rails 16 of the upper sash and the adjacent side members 10 of the window frame, I arrange a strip 20. 20 These strips extend from the bottom to the top of the frame and as they are held in position by the upper and lower sashes, it is unnecessary to attach the same to the window frame as such strips are intended to be free to move laterally 25 against the rear beads 15. If desired, the strips 20 may be loosely secured to the window frame by means of a slot and screw connection such as illustrated in my prior patent, which arrangement permits limited lateral movement of said 30 strips. As above noted, the upper sash is arranged between the strips 20 on opposite sides of the frame.

The lower or inner sash of the window includes side rails 21, an upper rail 22, and a lower rail 35 23. The side rails 21 of the inner or lower sash are arranged to abut against the strips 20 heretofore described. In other words, the inner or lower sash is wider than the outer or upper sash to the extent of the thickness of the strips 20. 40

One of the features of my present improvements involves the use of a storm sash positioned below the upper sash and outwardly of the lower sash. This storm sash includes a top rail 25, a bottom rail 26 and side rails 24, which side rails 45 abut against the rear beads 15 of the frame. The storm sash like the upper sash is positioned between the side strips 20 heretofore described. To maintain the storm sash in position when the inner sash is in its lowermost position, a lug or 50 projection 27 is secured to each side rail 24 and these lugs or projections are adapted to contact with the side rails 21 of the lower sash. By this construction, when the lower sash is pressed rearwardly as later described, the storm sash as well 55 as the side strips 20 and the upper sash of the window will be forced rearwardly against the rear beads 15. The meeting rails 18 and 22 of the upper and lower sash are so shaped and notched as to provide a tight joint and the same is true 60

of the meeting rails 16 and 25 of the upper sash and storm sash. The joint between the lower rail of the upper sash and the upper rail of the storm sash is such as to permit the storm sash to be tilted forwardly when the inner sash is raised or removed as shown in Figure 4 of the drawings.

The inner edge of each of the strips 20 is provided with a bead 20a which extends substantially from the top of the strip to the lower rail 18 of the outer sash and this sash is arranged to slide between said beads 20a and the rear beads 15.

The upper ends of the strips 20 form tongues 20b which are adapted to be inserted behind a transverse bead 28 on the frame, which bead acts as a stop to limit the forward movement of the strips 20.

As previously noted, an important feature of my improved construction lies in the front bead 30 and in its combination with other features. This bead is made up of a front or relatively fixed part 30a which is adapted to be rigidly secured to the frame members 10 and a rear part 30b slidably supported in a rabbet in the under surface of the front part 30a, preferably by means of a series of pins 30c passing through the part 30b and into the part 30a. Arranged between the parts 30a and 30b are several flat springs 30d which tend to force the part 30b rearwardly, or against the side rails of the inner sash when the beads and the sash are in position in the window frame.

It will be noted that the springs 30d are somewhat wider than the parts 30b so that the inner edges of said springs project into a longitudinal groove 30e formed in the part 30a and extending laterally of the rabbet in the part 30a of the bead. This arrangement forms a shoulder to engage the springs by which means the outward movement of the part 30b is limited. The springs 30d and the pins 30c thus serve to hold the parts of the beads 30 in assembled relation when they are removed from the window frame.

The outer edge of the parts 30b of each bead 30 is beveled or inclined as shown at 30f and the side rails 21 of the inner sash are correspondingly beveled on their inner corners adjacent the window frame as shown at 21a. The springs 30d normally force the parts 30b toward the rails 21 and the surfaces 30f thus fit against and cooperate with the beveled surfaces 21a on the rails. By reason of the cooperating beveled surfaces 30f and 21a it will be seen that the inner sash will be firmly but yieldably held against lateral movement in the window frame so that rattling of the window sash is prevented, but at the same time a close fit between the bead and the sash is maintained at all times regardless of the shrinking or swelling of the sash, and all danger of the sticking of the sash in the frame is obviated.

To hold the beads 30 in position at their upper ends, each is cut away to provide an inclined portion and a tongue which cooperate with a transverse bead 32 as fully described in my prior patent. In addition each bead 30 on its inner surface is provided with one or more inclined lugs or pins 33 which engage correspondingly inclined holes in the side members 10 of the frame. These pins 33 are inclined inwardly or away from the lower sash so that they act in the nature of hooks to secure the beads in place. The outwardly inclined surfaces 30f on the beads combined with

the inwardly inclined pins 33 produce a wedge effect on the beads so that they are firmly held in place against accidental displacement especially when the inner sash is down. By raising this sash the beads can be easily sprung or forced inwardly a sufficient extent to detach them from the frame when secured.

It is sometimes desirable to use the storm sash as a ventilator for the window. This can be done with my improved construction. When the inner sash of the window is raised, the upper end of the storm sash can be tilted inwardly to the position shown in Figure 4, in which position it rests against the beads 30. To permit such inward tilting, the upper portion of each side rail 24 of the storm sash is cut away as indicated at 34, the bottom of said cut away portions being inclined so as to rest against the outer edges of the beads 30 when the storm sash is thus tilted inwardly. The beads 30 thus serve to hold the storm sash in position to act as a ventilator. When complete removal of the storm sash is desired, one or both of the beads 30 are removed and the sash can then be withdrawn inwardly.

From the foregoing the construction and operation of my improved structure will be apparent and changes may, of course, be made in the details thereof. For example, a screen sash formed like the storm sash may be used and either metal or wood may be employed in my construction.

Having thus described the invention, what is claimed as new and desired to be secured by Letters Patent is:

1. A window construction comprising, in combination, a window frame, an upper or outer sash in said frame, an inner or lower sash vertically movable in said frame, and a storm sash arranged in said frame below said upper sash and outside of said inner sash, and cooperating means on said storm sash and said inner sash for holding said storm sash in position when the inner sash is down.

2. A window construction comprising, in combination, a window frame, an upper or outer sash in said frame, an inner or lower sash vertically movable in said frame, a storm sash arranged in said frame below said upper sash and rearwardly of said inner sash, and cooperating means on said lower sash and said storm sash for holding the latter in position when the lower sash is down, said storm sash being free to tilt inwardly when the inner sash is raised.

3. A construction as specified in claim 2 having means on said frame for yieldingly pressing said lower sash toward said storm sash.

4. A window construction comprising, in combination, a window frame, an upper or outer sash in said frame, an inner or lower sash vertically movable in said frame, a bead secured to said frame on each side of said lower sash and inwardly thereof, for holding the same in position, a storm sash arranged in said frame below said upper sash and rearwardly of said lower sash, said storm sash being tiltable inwardly when said inner sash is raised, said storm sash having the side rails thereof cut away to provide shoulders for resting against said beads when the same is tilted inwardly, whereby the storm sash is held in an inclined position to form a ventilator for the window.

JOSEPH V. DESMARAIS.
